Primary Examiner — Kelley Donnelly*(74) Attorney, Agent, or Firm* — JoAnn M. Seaton; Griffiths & Seaton PLLC(57) CLAIM

The ornamental design for a divided plate, as shown and described.

DESCRIPTION

FIG. 1 is a front, perspective view of a divided plate showing a first embodiment of our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a front, perspective view of a divided plate showing a second embodiment of our new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The features shown in broken lines are portions of the divided plate forming no part of the claimed design. The features shown in long dash-short dash bolded broken lines indicate the bounds of the claimed design and otherwise form no part of the claimed design.

1 Claim, 8 Drawing Sheets(56)
